UNITED STATES PATENT OFFICE

WILLIAM B. STODDARD, OF STAMFORD, CONNECTICUT, AND ROBERT V. TOWNEND AND VAMAN R. KOKATNUR, OF KEARNY, NEW JERSEY, ASSIGNORS TO PILOT LABORATORY, INC., OF ARLINGTON, NEW JERSEY, A CORPORATION OF NEW JERSEY

UNSYMMETRICAL ORGANIC PEROXIDE BLEACHING AGENT AND METHOD OF PREPARING THE SAME

No Drawing.

Application filed September 8, 1928. Serial No. 304,838.

Our present invention relates to a process of and composition for bleaching organic materials, such as flour and other milling products, oil seed meals, soaps, waxes, oils, 5 fats, egg yolk and other animal and vegetable products, etc. In its preferred embodiment, the invention relates more particularly to a process of and composition for bleaching such organic materials, and particularly food products by means of activated organic peroxides. The invention also relates to a process for making organic peroxides especially suited for bleaching purposes.

Various organic peroxid compounds have 15 heretofore been proposed for use in the bleaching of milling products such as flour, and of fats and oils. These peroxids, of which benzoyl peroxid is a type, have a relatively slight bleaching action in proportion 20 to the quantity of available oxygen contained in the compounds. Moreover, as they are only slightly soluble in oils, or other available solvents, the effectiveness of their use as oxidizing agents is limited, in many instances, 25 by the difficulty or inability to bring them into sufficiently intimate contact with the materials to be oxidized, more particularly when the coloring or chromophoric material is dissolved or otherwise incorporated in an oily 30 vehicle or carrying medium.

These various disadvantages are overcome and obviated in our present invention, one object of which is to provide a more efficient and effective oxidizing composition and one 35 having maximum bleaching action per unit of oxidizing power.

Another object of the invention is to provide a readily soluble oxidizing composition suitable for the bleaching of organic products, 40 and particularly of food products.

Another object is to provide an organic peroxid that is soluble in oils or other vehicles in which the coloring matters to be bleached are dissolved or carried, and to increase the solubility of organic peroxids in 45 such vehicles.

Further objects and features of the invention are to provide organic peroxids which have an activating action on other organic peroxids to thereby increase the effectiveness 50

of the oxidizing or bleaching action of such peroxids per unit of available oxygen; to provide a process of preparing such soluble and activating peroxids, and to provide improved methods of bleaching organic materials.

In accordance with our invention, the solubility and effectiveness of the peroxid bleaching agent is attained by forming a double or complex peroxid of benzoyl or its derivatives, and acyl compounds of materials that are constitutionally similar or related to the chromophoric oils of carotinoids, and particularly similar or relating to the fatty acid constituents of oils and fats. The fatty material is preferably combined with the benzoyl group in the proportion of one molecule of benzoyl to one or more molecules of fatty or oily constituents, so that the benzoyl portion in no case exceeds the proportion, by weight, of the fatty acid. In the complex peroxid or mixture of complex peroxids thus formed, an acyl group of a fat is substituted for a benzoyl group in dibenzoyl peroxid. The resulting peroxid or peroxids may be represented by the formula

in which R CO represents an acyl group of a fatty acid of a fat or oil.

When the acyl group of a higher fatty acid, that is, butyric or higher acids, which are of an oily or waxy nature, is used for the substituted acid group, the resulting peroxid has the property of being soluble in, and miscible with oils or oily solvents and peroxids of other fatty acids. Thus, while benzoyl peroxid is soluble in petroleum solvents to but a negligible per cent, peroxids whose benzoyl portions is about $\frac{1}{6}$ th of the fatty acid portion, are soluble to almost any extent in these solvents, while a peroxid whose benzoyl portion is about $\frac{1}{2}$ or more of the fatty acid portion is miscible in all proportions of the same solvent. It also has the capability, whether due to a greater or less degree to this solubility or to catalytic action, or other causes, of activating other organic peroxids, which would otherwise be relatively inactive and sluggish and, therefore, inef-

fective as bleaching agents. This property of rendering the complex peroxid relatively soluble and an activating agent does not, however, result when there is used for the complex peroxid a lower fatty acid, such as acetic acid, which is water soluble and is not of a fatty or oily nature as are the higher acids, though it is in its chemical constitution a homologue of the higher fatty acids. It is, therefore, to be understood that the higher fatty acids, i. e., those of an oily or waxy nature and which may, for convenience, be designated as soap-forming acids, are to be used as the substituted group.

The higher fatty acids referred to herein may be saturated or unsaturated, or may be acids that were originally unsaturated, but which have been saturated by hydrogenation or the addition of elements or radicles.

The effectiveness of our bleaching agent is, therefore, greatly increased by its greater solubility in the materials that are to be bleached, or in the oils containing the chromophoric material to be oxidized. The solubility of the complex fatty benzoyl peroxid in a common solvent of the oily chromophoric constituents of the material to be bleached also contributes to its effectiveness and availability for the bleaching action, as it enables it to be brought into a uniformly distributed, homogeneous solution in such oily constituents and, therefore, in a more effective state for reaction therewith than is the case of peroxids that are not soluble in an oily solvent.

The material is, therefore, particularly adaptable to the method of bleaching in which it is dissolved in an oil which is then sprayed, or otherwise disseminated, throughout the material to be bleached, and is thereby brought into most intimate contact with the chromophoric oils, or other material, to be acted upon.

The fatty acid compound to be peroxidized with the benzoyl group may be a suitable compound of either a single acid, or a derivative of a single acid, or a mixture of acids, either a naturally occurring mixture such as exists in cocoanut oil, or an artificial mixture or blend of acids. The complex peroxid or mixture of complex peroxids may be obtained by peroxidizing the benzoyl and fatty acid compounds in any suitable manner. Preferred methods of forming the complex or mixed peroxids are illustrated in the following examples:

Example I

In preparing the benzoyl-fatty and complex peroxids, our preferred practice is as follows:

In a suitable vessel, fitted with any desired means of vigorous agitation, are placed 700 cc. of 7.5% hydrogen peroxid and 100 cc. of 1% soap solution. This mixture is then

cooled by adding chipped ice. Then 200 cc. of a solution of caustic soda containing 343 grams NaOH per 100 cc. are added to the chilled mixture, and the mixture is kept cold by the addition of ice. While the solution is being agitated there is added to it 250 grams of a mixture of acid chlorides of cocoanut oil and benzoyl chloride in the proportion of 232 grams of the chlorids of the total acids of cocoanut oil of an average molecular weight of about 223, and 124 grams of benzoyl chlorid. The mixture is agitated for about seven minutes, keeping the temperature low by the continued addition of chipped ice. The mixture should contain small pieces of ice at all times. During this operation, the peroxids emulsify and the solution becomes like milk. At the end, the solution is rendered slightly acid with sulfuric acid which causes the emulsion to break and watery layer forms at the bottom which may be drawn off. The mixture of complex peroxids is then melted by the addition of warm water, the water separated, and the product dried and filtered.

We often find it desirable to use as a bleaching agent, a solution of the benzoyl-fatty acid peroxid complex in a mineral oil such as Marcol. This solution may be prepared by adding the desired amount of the solvent to the complex peroxid at any stage of the operation after the peroxidizing action, as given above, has been completed. Analyses show that the product contains a very high percentage of the active oxygen theoretically possible. We have also found that benzoyl peroxid is but very slightly soluble in fatty acid peroxids, and still less so in mineral oils. Consequently, the high solubility of our product in a mineral oil solution to form a solution which is clear and free from solids, evidences that the peroxids are present in the form of a true complex or a mixture of such complexes.

Example II

In a suitable vessel, fitted with an agitator, is placed about 1100 cc. of 7.5% hydrogen peroxid. This is cooled to about 0° by the addition of chipped ice. To this are added about 1575 cc. of 1% soap solution and 400 cc. of a solution of caustic soda containing 343 grams NaOH per 1 litre. The mixture is agitated and kept cold by the addition of ice. To this solution, while being agitated, are added 500 grams of a mixture of acid chlorids containing one part by weight of benzoyl chlorid, or its derivatives, and five parts by weight of the chlorids of the total fatty acids of cocoanut oil, or their derivatives. Agitation is continued about seven minutes with constant additions of ice, which should be present at all times during the reaction. The product forms an emulsion which is broken by rendering the solution slightly acid with sulfuric acid. The mixture of peroxids can

now be separated, melted, dried and filtered, as in Example I. They may also be dissolved in mineral oil, or other solvents at will, as described in the first example.

The chlorids of the total acids of cocoanut oil used in Examples I and II, has an average molecular weight of 223.5, and the molecular weight of benzoyl chloride (C_6H_5COCl) is 140.5. To form the complex, one molecule of each is required. As the proportions cited in the second example call for more of the fatty acid chlorids than the above ratio (140.5 parts of benzoyl chloride to 223.5 parts of the chlorids of the fatty acids) it is evident that the peroxids formed must contain the peroxids of the fatty acids in addition to the complex. We have found that these fatty acid peroxids, while themselves good bleaching agents, can be made more efficient in their bleaching action by producing them in connection with the complex, which simultaneously produces, of itself, two peroxids, as in Example II.

The above product (second example) contains the required activator in the form of the benzoyl-fatty acid peroxid complex, and is found to be very active and satisfactory in its bleaching effect. Although the group of fatty acids whose glycerides form the major portion of cocoanut oil have been described specifically in the above examples, it is to be understood that other groups of higher fatty acids occurring in any natural fat or oil, or any individual acid therein, or mixtures containing a smaller number of acids than the total represented in any fat or oil, or mixtures of fatty acids from different sources may be employed. The addition and substitution products of such individual fatty acids or groups or mixtures of the fatty acids may also be employed.

Our invention, therefore, provides a more efficient bleaching agent and one in which the available oxygen is utilized most efficiently and effectively. In addition, it provides a bleaching agent capable of activating less active bleaching agents and of rendering their potentially available oxygen content effective and efficiently usable. As our peroxid is soluble in materials of the nature associated with the coloring matter to be oxidized, the oxidizing agent reacts in a solution in, and in intimate contact with, the coloring matter, rather than in the heterogeneous state of mixed powders.

As changes of operation could be made within the scope of our invention, it is intended that all matter contained in the above description shall be interpreted as illustrative and not in a limiting sense.

Having now described our invention, what we claim as new and desire to secure by Letters Patent is:

1. A peroxid of the general formula $R-CO-O-O-OC-R_1$ in which R_1 is an

aromatic radical and $R-CO$ corresponds to an acyl radical of a mono-basic aliphatic acid having not less than four carbon atoms.

2. An oil soluble peroxid of the general formula $R-CO-O-O-OC-R_1$ in which R_1 is an aromatic radical and $R-CO$ corresponds to an acyl radical of a mono-basic aliphatic acid having not less than four carbon atoms. 70

3. A peroxid of the general formula $R-CO-O-O-OC-R_1$ in which R_1 is the phenyl radical and $R-CO$ corresponds to an acyl radical of a mono-basic aliphatic acid having not less than four carbon atoms. 75

4. An oil soluble mixture of peroxids of aromatic carboxylic acids and mono-basic aliphatic carboxylic acids having not less than four carbon atoms and of a peroxid of the general formula $R-CO-O-O-OC-R_1$ in which R_1 indicates an aromatic radical and $R-CO$ corresponds to an acyl radical of a mono-basic aliphatic acid having not less than four carbon atoms, the molecular proportion of the fatty acid peroxid constituent being greater than that of the aromatic peroxid constituent. 80

5. An oil soluble mixture of the peroxids of benzoic acid, of a mono-basic aliphatic carboxylic acid of not less than four carbon atoms and of a peroxid of the general formula $R-CO-O-O-OC-R_1$ in which R_1 indicates the phenyl radical and $R-CO$ corresponds to an acyl radical of a mono-basic aliphatic acid having not less than four carbon atoms, the proportion of said fatty acid peroxid constituent being greater than that of the benzoyl peroxid constituent. 95

6. An oil soluble peroxid of the general formula $R-CO-O-O-OC-R_1$ in which R_1 corresponds to the phenyl radical and $R-CO$ corresponds to an acyl radical of a mono-basic aliphatic acid having not less than four carbon atoms. 105

7. An oil soluble peroxid of the general formula $R-CO-O-O-OC-R_1$ in which R_1 indicates an aromatic radical and $R-CO$ corresponds to an acyl radical of a mono-basic aliphatic acid having not less than four carbon atoms. 110

8. An activated organic peroxid which comprises a mixture of an organic peroxid and of a peroxid of the general formula $R-CO-O-O-OC-R_1$ in which R_1 indicates an aromatic radical and $R-CO$ corresponds to an acyl radical of a mono-basic aliphatic acid having not less than four carbon atoms. 115

9. An activated organic peroxid which comprises a mixture of an organic peroxid and of a peroxid of the general formula $R-CO-O-O-OC-R_1$ in which R_1 indicates the phenyl radical and $R-CO$ corresponds to an acyl radical of a mono-basic aliphatic acid having not less than four carbon atoms. 125

10. A process of making peroxids which comprises treating a mixture of acid chlorids of mono-basic fatty acids having not less than four carbon atoms and benzoyl chlorid with a peroxidizing material.
11. A method of forming complex peroxids which comprises treating acid chlorids of mono-basic fatty acids having not less than four carbon atoms and benzoyl chlorid with an alkaline solution of hydrogen peroxid.
- 10 12. A process of forming a complex peroxid which comprises treating a mixture of acid chlorids of mono-basic fatty acids having not less than four carbon atoms and benzoyl chlorid with an alkaline solution of hydrogen peroxid.
- 15 13. The process of forming mixed peroxids which comprises treating a mixture of mono-basic fatty acid chlorids having not less than four carbon atoms and benzoyl chlorid with an alkaline solution of hydrogen peroxid and soap.
- 20 14. A process of forming complex peroxid which comprises treating a mixture of acid chlorids of cocoanut oil and benzoyl chlorid with a chilled alkaline solution of hydrogen peroxid and soap, acidifying the resulting emulsion and separating the resulting peroxid.
- 25 15. An oil soluble mixture comprising a mixture of the peroxids of mono-basic fatty acids having more than four carbon atoms and of peroxids of the general formula R—CO—O—O—OC—R₁ in which R₁ indicates the phenyl radical and R—CO corresponds to an acyl radical of a mono-basic aliphatic acid having not less than four carbon atoms.
- 30 40 In witness whereof we have hereunto set our hands this 22d day of August, 1928.
